UNITED STATES PATENT OFFICE.

JOHN W. K. HODGE, OF BLAIR STATION, PENNSYLVANIA, ASSIGNOR OF ONE-FOURTH TO EWALD E. BAHR, OF BLAIR STATION, PENNSYLVANIA.

ROTARY STEAM-ENGINE.

SPECIFICATION forming part of Letters Patent No. 709,323, dated September 16, 1902.

Application filed July 20, 1901. Serial No. 69,132. (No model.)

To all whom it may concern:

Be it known that I, JOHN W. K. HODGE, a citizen of the United States, residing at and whose post-office address is Blair Station, in 5 the county of Allegheny and State of Pennsylvania, have invented new and useful Improvements in Rotary Steam-Engines, of which the following is a specification.

My invention relates to rotary steam-engines; and its primary object is to provide an 10 improved construction of engine whereby the complete expansive force of the steam will be utilized.

A further object of the invention is to obtain 15 a uniform pressure and a correspondingly uniform development of power at every point in each revolution, thereby avoiding the employment of a heavy balance-wheel to supply momentum while passing centers.

20 A further object of the invention is to employ a plurality of pistons, preferably eight, in series in independent cylinders and relatively arranged at equal angles to one another, preferably forty-five degrees, thereby 25 maintaining a maximum mean effective pressure with the minimum expansion.

A further object of the invention is to provide improved means for operating the inlet and cut-off valves, whereby the same mechanism 30 which controls the cut-off valves will serve to control the supply of steam to the several cylinders.

With the above and such other objects as may be disclosed in the following description 35 the invention consists in the improved construction of rotary engine hereinafter fully described in connection with the accompanying drawings, which form a part of this specification, the novel and characteristic features 40 of which will be defined in the appended claims.

In the drawings, Figure 1 is a front elevation of a rotary engine embodying the invention. Fig. 2 is an end view of the same. 45 Fig. 3 is a transverse vertical section. Fig. 4 is a perspective view of a section of one of the cylinders. Fig. 5 is a detail perspective of one of the piston-disks and its piston mounted upon the engine-shaft. Fig. 6 is a 50 perspective view of the cam-shaft and its cams for operating the abutments and the in-

let-valves of the engine. Fig. 7 is a vertical transverse section through one of the cylinders, showing in dotted lines the relative arrangement of the several pistons.

Referring to the drawings and especially to Figs. 1 and 2, the numeral 1 designates a rigid frame, which may be of any suitable construction, to support the series of cylinders 2, and said frame is provided with bearings, as 3, for the rotary shaft 4, upon which is fixed a suitable band-pulley 5 or equivalent power-transmitting element.

As shown in Fig. 1, the several cylinders are arranged side by side in parallel relation 65 and firmly bolted together to constitute substantially a single structure.

In the carrying out of my invention I employ eight of these cylinders, as that number permits of the employment of eight pistons 70 disposed at an angle of forty-five degrees apart, which I have found the most effective number and arrangement of pistons for the purpose in view; but I would have it understood that a greater or less number of cylinders and pistons might be employed without departing from the invention.

As each of the cylinders and the operative mechanism associated and combined therewith are of the same construction a description of one will suffice for all.

Each cylinder consists of a hollow ring made of sections, such as shown in Fig. 4, continuous parallel flanges 6 being provided for connecting the several rings together.

85 A continuous slot 7 is formed in the inner surface of the ring, communicating with the circular interior 8 of the ring and adapted to receive a piston-disk 9, which fits revolvably between the walls of the slot 7, the latter being suitably packed to insure steam-tight joints.

Upon the disk 9 is secured a circular piston 10, projecting from one side of the disk and adapted to fit the circular space within the 95 ring.

As illustrated by the dotted lines in Fig. 7, the eight pistons employed are so arranged within the cylinders as to be at an equal distance (forty-five degrees of a circle) apart radially.

Projecting at a radial angle from the face

of each cylinder or ring adjacent to the bottom thereof is an abutment-casing and guide 11, communicating with the interior of the cylinder by a slot 12 and adapted to receive 5 and guide a sliding abutment 13, arranged to close the steam - passage 8 in the cylinder. The abutment is provided with a stem 14, which is pivotally connected by a link 15 to the outer end of a lever 16, fulcrumed on a 10 shaft 17, supported by the frame, the other end of the lever being 16 being arranged in the path of one of the cam-arms 35. The lever 16 is pivotally connected at a point below its fulcrum to the upper end of a rod 18 of a 15 dash-pot 19.

In front of the slot 12 of the cylinder through which the sliding abutment 11 works is a steam-inlet 20, extending through the abutment - casing and communicating by 20 means of a pipe 21 with a steam-supply pipe 22. There is a separate steam-supply pipe 22 for each ring or cylinder, said pipes connecting with a main-supply pipe 22^a.

The end of the supply-pipe 22 communicates with a valve-casing 23, within which reciprocates a valve 24 for controlling the supply of steam to the cylinder, and having a suitable valve-stem 25, pivotally secured to one end of a rocker-bar 26, pivotally secured 30 upon a shaft 27 and adapted to be raised by the means hereinafter referred to and to fall by gravity.

28 designates the exhaust-port of the cylinder, communicating by means of a pipe 29 35 with a condenser 30, which may be of the usual or any preferred construction and constitutes no part of the present invention. I, however, preferably employ the form of condenser which comprises a coil of pipe for 40 cold water, with means, as shown at 31, for forcing the water of condensation back to the boiler.

Below the series of cylinders is located a cam-shaft 32, supported in suitable bearings 45; and connected by a sprocket-chain 33 and sprocket - wheel 34 or equivalent means to the engine-shaft 4.

Projecting from the shaft 32 are a plurality of arms or cams 35, arranged radially at 50 angles of forty-five degrees to one another, so as to successively operate the several levers 16 and 26.

The operation of the engine constructed as above described is as follows: Steam is admitted to the first cylinder of the series 55 and after its piston has been driven a distance equal to one-eighth of a revolution steam enters the second cylinder, and so on, the eight pistons receiving the impact of 60 steam successively at each eighth of a full revolution. The relative arrangement of the pistons is an essential characteristic of the invention and serves two important purposes—to wit, by admitting a fresh supply of 65 steam eight times during a single revolution it brings the average mean effective pressure up to the maximum, and, secondly, after

the steam enters behind each piston it may expand from thirty-two to ninety-six times its bulk or down to a minimum pressure before exhausting into the condenser. 70

The cam-shaft 32 and its series of operating arms or cams, as above stated, cause the sliding abutments 13 to move outward successively to permit the passage of the pistons, and the dash-pots 19 return the abutments to their inner positions. 75

The arms or cams 35 are of sufficient width to elevate the levers 26 as well as the levers 16, (said levers being in different vertical 80 planes,) and are so disposed with relation to said levers as to operate the two levers 26 and 16 alternately to admit steam and move the abutment 13 inward and cut off steam when the sliding abutment is moved outward 85 into the casing 11.

I reserve the right to make all such changes and modifications in the details of the engine as may be resorted to without departing from the spirit of the invention or may fall within 90 the scope of the following claims.

I claim—

1. In a rotary engine, the combination with a hollow ring having a continuous slot in its inner surface communicating with the interior of the ring; of a disk revolubly mounted in the ring and extending into the slot, a piston projecting from the disk and fitting the interior of the ring, an abutment-casing projecting from the ring, a sliding abutment in 100 said casing, a steam-inlet to the ring, a valve thereto, levers connected to the valve and abutment respectively, a rotary shaft, and a projection thereon adapted to operate the levers of the valve and abutment successively. 105

2. In a rotary engine, a series of slotted hollow rings, each containing a revoluble disk, pistons upon the disks and fitted in their respective rings, an inlet and an exhaust to each ring, a valve to regulate the flow of steam 110 through the inlets, a sliding abutment in each ring, a revoluble shaft, and a projecting arm thereon for each ring, each arm being adapted to successively operate the abutment and the inlet-valve of its ring. 115

3. In a rotary engine, the combination with a slotted hollow ring; of a shaft, a disk mounted thereon and revoluble in the slot, a piston upon the disk and mounted in the ring, an inlet-valve and sliding abutment in the ring, 120 a pivoted lever pivoted at one end to the abutment, a pivoted lever pivoted at one end to the inlet-valve, a revoluble shaft driven from the shaft of the disk, and an arm extending therefrom and adapted to successively contact with, and operate, the levers of the abutment and the inlet-valve. 125

4. A rotary engine comprising a casing formed of a series of similar slotted hollow rings, each of said rings having flanges for the reception of fastening means, whereby the rings are fastened together, a revoluble shaft extending through the rings, disks, secured to the shaft, one disk extending into the slot 130

of each ring, a steam-inlet pipe opening into the ring, a valve to control the entrance of steam through the pipe, a sliding abutment in each ring, a piston upon each disk, said 5 pistons being adapted to work in the rings, a pivoted lever connected to the inlet-valve, a similar lever pivoted to the sliding abutment, a shaft driven from the piston-shaft, and radially-disposed arms thereon at equal angles

to each other, each arm being adapted to successively operate the abutment and the inlet-valve of its ring.

In testimony whereof I affix my signature in presence of two witnesses.

JOHN W. K. HODGE.
